DESIGN FOR A SCISSORS SHARPENER

Ruth C. Lathom, Gillette, Wyo.

Application December 31, 1947, Serial No. 143,484

Term of patent 3½ years

(Cl. D37—1)

To all whom it may concern:

Be it known that I, Ruth C. Lathom, a citizen of the United States, residing at Gillette, in the county of Campbell, in the State of Wyoming, have invented a new, original, and ornamental Design for a Scissors Sharpener, of which the following is a specification, reference being had to the accompanying drawing, forming a part thereof.

Fig. 1 is a side elevational view of a scissors sharpener, showing my new design; Fig. 2 is a front elevational view of the same; Fig. 3 is a rear elevational view of the same; and Fig. 4 is a top plan view of the same.

I claim:

The ornamental design for a scissors sharpener, as shown.

RUTH C. LATHOM.
